HINGED FUNNEL.

1,309,055.

Specification of Letters Patent.

Patented July 8, 1919.

Application filed January 3, 1917. Serial No. 140,378.

To all whom it may concern:

Be it known that I, JOHN W. ANDERSON, a citizen of the United States, and a resident of New London, in the county of New London and State of Connecticut, have invented 5 certain new and useful Improvements in Hinged Funnel; and I do hereby declare the following to be a full, clear, and exact description of the invention, such as will 10 enable others skilled in the art to which it appertains to make and use the same.

This invention relates to submarine boats. Such a vessel, when fitted with steam power 15 for surface propulsion must be provided with some form of funnel for the escape of surplus steam and the gases of combustion, and yet when the boat is submerged all openings must be closed tight and all external parts of the funnel must be stowed away in 20 order to reduce the boat's resistance to submerged propulsion.

In some cases telescopic funnels have been suggested; but to these there are serious 25 practical objections. In the first place the height of the funnel should not be such as to prevent a substantially complete telescoping of the funnel down into the superstructure, and yet the funnel must be high enough for satisfactory service in carrying off the 30 surplus steam and the products of combustion. The telescoping organization, moreover, even if a unitary funnel is used, necessitates unsatisfactory complications of parts, joints, &c.

In other cases the attempt has been made 35 to pass the gases up through passages built permanently into the superstructure; but the disadvantages of such an arrangement are too obvious to need discussion.

The present invention involves the provision 40 of a unitary stack or funnel hinged to the hull in the lower part of the superstructure space adjacent to the upper mouth of the boiler uptake and movable to and from 45 a substantially vertical position in continuation of the uptake, a hinged door adapted to be swung to open the intake as the stack is moved to its vertical position and to close the intake as the stack is moved away from 50 its vertical position, and means for thus operating the stack and the door controlled

from within the boat. The stack is of greater length than the height of the superstructure space, and accordingly an elongated opening is provided in the superstructure deck so that the stack may be swung away from its vertical position and through the opening for stowage below the deck. 55

One of the objects of the invention is to provide a reliable, rugged and conveniently 60 actuatable means which may be employed for operating the stack from the interior of the vessel, which means is self-locking in all positions of the stack.

Another object is to provide, as a movable 65 part of the escape steam line of the boiler, an auxiliary stack, funnel or escape pipe preferably similarly mounted and similarly controlled. To this end it is preferred to have the fixed part of the steam line from 70 the boiler terminate adjacent to the uptake, to mount the auxiliary steam pipe on the hinged stack in position to form a continuation of the fixed steam pipe when the stack forms a continuation of the uptake, and to 75 arrange the door so that it closes the fixed steam pipe when it closes the uptake.

In the accompanying drawing, illustrating 80 the preferred embodiment of the invention,

Figure 1 is a vertical sectional view showing the stack horizontal and the door in closed position;

Fig. 2 is a view similar to Fig. 1, showing 85 the stack vertical and the door in open position; and

Fig. 3 is a sectional view taken on the line 3—3 of Fig. 2.

4 indicates the hull of the boat. A permanently built-in open-topped steam pipe 5 90 leads from a safety valve 6 carried by the boiler 7. This pipe 5 extends above the hull roof, as does a permanently built-in open-topped passage or uptake 8 leading from the combustion chamber (not shown) of the 95 boiler.

A stack 9, for forming a continuation of the uptake 8 as shown in Fig. 2, is mounted on a hinged plate 10 fixed on a pintle or shaft 11, so that when the shaft is rotated 100 in a counter-clockwise direction the stack may be swung downward through an open-

ing 12 formed in a superstructure deck 13 and thus be uncoupled from uptake 8 and stowed in superstructure space 14.

The stack 9 and the auxiliary steam pipe 15 move as one unit, either to lie as shown in Fig. 1, when the stack and pipe form continuations of the uptake 8 and the pipe 5, or as shown in Fig. 2, when such parts are uncoupled. The pipe 15 is anchored adjacent to its lower end in a web 10' which is a part of the hinge plate 10 (Fig. 3) and is anchored adjacent to its upper end by means of a bracket 16. Opening 12 may or may not have associated therewith an adjustable cover, but if such a cover is provided it need only be adapted for making a spraytight closure.

Ordinarily for cruising in light seas and when the stack and the auxiliary pipe are disconnected, the portions of pipe 5 and uptake 8 which project above the hull-roof act as protective coamings; but preparatory to submergence it is necessary to close the pipe 5 and the uptake 8 in a watertight manner. In the present instance, a single door 17 forms a part of a hinge-plate 18 secured to a pintle or shaft 19. A single door for the purpose specified is very desirable, and this is made possible by bringing together in one place on the roof of the hull all openings which serve the boiler plant. This door 17 (Figs. 2 and 3) is provided on its underside with a well 17^a for closing pipe 5 in a watertight manner, and with a well 17^b for similarly closing uptake 8 when shaft 19 is rotated in a counter-clockwise direction to lie as disclosed in Fig. 1.

According to the present construction, when the stack 9 and door 17 are being changed from the locations of Fig. 1 to those of Fig. 2, or vice versa, the stack swings through an angle of 90° and the door through an angle twice as large. Parts of the door and stack, moreover, have intersecting arcs of movement as indicated by broken line arrows in Fig. 1. The swinging movements of the door and stack should, however, be so correlated that the door closes the uptake as soon as possible after the stack commences to leave its vertical position, and yet so that in moving the stack to its vertical position the stack takes up such position just as the door takes up the location of Fig. 2. The mechanism controlling all these operations, in order to be self-locking, should have its various elements positively interconnected and positively actuated. These ends are attained as follows:

The movements of the door 17 are controlled by the rotations of beveled gear 20 fixed on a sleeve 21 (Fig. 1) journaled in bearings 22, the sleeve having secured to its opposite end a spiral gear 23 which meshes with a spiral gear 24 fixed on pintle or

shaft 19. The movements of stack 9 are controlled by the rotations of beveled gear 25 fixed on a shaft 26 loosely extending through sleeve 21, the shaft 26 having secured to its opposite end a spiral gear 27 which meshes with a spiral gear 28 fixed on pintle or shaft 11. These beveled gears 20 and 25 are both actuated by a mutilated bevel gear 29 with which they are adapted to mesh; the gear 29 being fast on the upper end of a vertical shaft 30 on the lower end of which is fixed a worm gear 31 co-operating with a worm 32 on the same shaft with and driven by a hand-wheel 33 located within the hull.

With the parts arranged as shown in Figs. 2 and 3, to redispone them as disclosed in Fig. 1 hand-wheel 33 is turned in the direction of the arrow *a* marked thereon, to cause all the gears above mentioned to turn in the directions of their arrows *a*. As a result the mutilated gear 29 first causes the stack 9 to swing downward as shown in Fig. 1, at the same time moving the door from the location of Fig. 2 to a position intermediate its open and closed positions. As soon as the stack becomes disposed as shown in Fig. 1, the portion 29' of the gear 29 comes opposite the gear 25, and the latter gear then becomes idle, so that further rotation of the gear 29 causes a rotation merely of the gear 20 to move the door to close the uptake. Just as this last movement is completed, the gear 29 again meshes with gear 25, while remaining in mesh with gear 20, the mutilated portion 29' of gear 29 now being in the location 29''; and so the stack and door are positively locked in the positions of Fig. 1.

With the parts arranged as shown in Fig. 1, to redispone them as disclosed in Figs. 2 and 3 the hand-wheel 33 is turned in the opposite direction to that of the arrow *a* marked thereon, all the other gears then turning in directions opposite to their arrows *a*. The mutilated portion 29' of the gear 29 being at the location 29'', the first part of the rotation of gear 29 rotates merely the gear 20, leaving the gear 25 temporarily idle. As a result, the door is swung sufficiently away from the uptake to permit the stack to be swung up toward its vertical position. This accomplished, the gear 29 again comes into mesh with the gear 25, and, remaining in mesh with the gear 20, completes the readjustment of stack and door by simultaneously moving them to take up the locations of Figs. 2 and 3.

I claim:—

1. In a submarine boat equipped with a steam power plant, in combination, a hull provided with an opening, a boiler-uptake leading to said opening, a pivotally mounted funnel, means for moving the funnel to ex-

- tend substantially horizontally and away from said opening and to extend substantially vertically and above said opening, a movable door for opening and closing said opening, and means operable from within the boat for turning the funnel about its pivot and also for moving the door.
5. In a submarine boat equipped with a steam power plant, in combination, a hull having two openings therein, a boiler-uptake leading to one opening, a funnel so mounted as to be movable to lie away from said opening and to extend substantially above said opening, a steam pipe leading 10 to the second opening, a second funnel so mounted as to be movable to lie away from the second opening and to extend substantially vertically and above the second opening, and movable closures for the two openings movable to close both the openings.
15. In a submarine boat equipped with a steam power plant, in combination, a hull having a plurality of openings therein, smoke and escape steam passages one passing through each of the openings, and a plurality of funnels hinged as one unit and movable as one unit to lie substantially horizontally and to extend substantially vertically with one of the funnels serving each 20 of said openings.
20. In a submarine boat equipped with a steam power plant, in combination, a hull having a plurality of openings therein, smoke and escape steam passages one passing through each of the openings, a plurality of funnels hinged as one unit and movable as one unit to lie substantially horizontally and to extend substantially vertically with one of the funnels serving each 25 of said openings, and means operable from the interior of the hull whereby said funnels may be moved as aforesaid.
25. In a submarine boat equipped with a steam power plant, in combination, a hull having a plurality of openings therein, smoke and escape steam passages one passing through each of the openings, a plurality of funnels hinged as one unit and movable as one unit to lie substantially horizontally and to extend substantially vertically with one of the funnels serving each 30 of said openings, and means operable from the interior of the hull whereby said funnels may be moved as aforesaid.
30. In a submarine boat equipped with a steam power plant, in combination, a hull having a plurality of openings therein, smoke and escape steam passages one passing through each of the openings, a plurality of funnels hinged as one unit and movable as one unit to lie substantially horizontally and to extend substantially vertically with one of the funnels serving each 35 of said openings, and means operable from the interior of the hull whereby said funnels may be moved as aforesaid.
35. In a submarine boat equipped with a steam power plant, in combination, a hull having a plurality of openings therein, smoke and escape steam passages one passing through each of the openings, a plurality of funnels hinged as one unit and movable as one unit to lie substantially horizontally and to extend substantially vertically with one of the funnels serving each 40 of said openings, and means operable from the interior of the hull whereby said funnels may be moved as aforesaid.
40. In a submarine boat equipped with a steam power plant, in combination, a hull having a plurality of openings therein, smoke and escape steam passages one passing through each of the openings, a plurality of funnels hinged as one unit and movable as one unit to lie substantially horizontally and to extend substantially vertically with one of the funnels serving each 45 of said openings, and means operable from the interior of the hull whereby said funnels may be moved as aforesaid.
45. In a submarine boat equipped with a steam power plant, in combination, a hull having a plurality of openings therein, smoke and escape steam passages one passing through each of the openings, a plurality of funnels hinged as one unit and movable as one unit to lie substantially horizontally and to extend substantially vertically with one of the funnels serving each 50 of said openings, and means operable from the interior of the hull whereby said funnels may be moved, closures hinged and movable as one unit to uncover and clear away from the openings and to close the openings, and means operable from the interior of the hull whereby the closures may be moved as aforesaid.
50. In a submarine boat equipped with a steam power plant, in combination, a hull having a plurality of openings therein, smoke and escape steam passages one passing through each of the openings, a plurality of funnels hinged as one unit and movable as one unit to lie substantially horizontally and to extend substantially vertically with one of the funnels serving each 55 of said openings, and means operable from the interior of the hull whereby said funnels may be moved, closures hinged and movable as one unit to uncover and clear away from the openings and to close the openings, and means operable from the interior of the hull whereby the closures may be moved as aforesaid.
55. In a submarine boat equipped with a steam power plant, in combination, a hull having a plurality of openings therein, smoke and escape steam passages one passing through each of the openings, a plurality of funnels hinged as one unit and movable as one unit to lie substantially horizontally and to extend substantially vertically with one of the funnels serving each 60 of said openings, and means operable from the interior of the hull whereby said funnels may be moved, closures hinged and movable as one unit to uncover and clear away from the openings and to close the openings, and means operable from the interior of the hull whereby the closures may be moved as aforesaid.
60. In a submarine boat equipped with a steam power plant, in combination, a hull having a plurality of openings therein, smoke and escape steam passages one passing through each of the openings, a plurality of funnels hinged as one unit and movable as one unit to lie substantially horizontally and to extend substantially vertically with one of the funnels serving each 65 of said openings but adapted to be swung away from the openings to assume a horizontal position, closing devices for the openings hinged as one unit and movable as one unit to uncover and clear away from the openings or to close the same, and means 70 including a single controller for swinging the funnels to the horizontal position and for moving the closures to close the openings.
7. In a submarine boat equipped with a steam power plant, in combination, a hull having an opening therein, a boiler uptake leading to the opening, a funnel hingedly connected to the boat for normally serving the uptake, a door also hingedly connected 75 to the boat, and operating means, having a single controller, for swinging the funnel through approximately 90° away from the uptake and for swinging the door through approximately 180° to close the uptake. 85
8. In a submarine boat equipped with a steam power plant, the combination of a hull having an opening in the top thereof, a steam boiler mounted within the hull, a short stationary stack extending upwardly 90 from the boiler to the opening in the hull, an escape steam pipe also stationarily mounted and extending upwardly from the boiler to the opening in the hull, a movable funnel and a movable steam pipe secured together so as to move as a single unit and pivotally mounted upon the hull of the boat so as to be movable to a substantially vertical position in line with the stationarily mounted stack and pipe, or to a substantially horizontal position close to the hull of the boat, and a superstructure upon the hull of the boat having an opening therein through which the movable funnel and pipe are projected when they are moved from 95 the horizontal to the vertical position. 100
9. In a submarine boat equipped with a steam power plant, in combination, a hull having two openings therein, a boiler uptake leading to one opening, a funnel 110 hingedly connected to the boat for normally serving the uptake, a pipe for escape steam leading to the second opening, a second funnel carried by the first funnel for serving the pipe when the first funnel serves the uptake, a superstructure deck having an opening through which such funnels then project, means operable from a distance for swinging the two funnels through the last-mentioned opening for stowage in the superstructure space, and means for thereupon closing the two first-mentioned openings actuated by the means last-mentioned. 115
10. In a submarine boat equipped with a steam power plant, in combination, a hull having an opening in the roof, a boiler uptake leading to the opening, a superstructure deck having an opening therein overlying the first opening, a funnel hingedly connected to the boat near the bottom of the 120 125
- 130

superstructure space and normally projecting through the opening in the superstructure deck and serving the uptake, means operated from within the hull for swinging the funnel away from the uptake and through the opening in the superstructure deck to arrange the funnel in the super-

structure space, and means in the superstructure space and operated also from within the hull for closing the uptake when 10 the funnel is swung away from the uptake.

In testimony whereof I affix my signature.

JOHN W. ANDERSON.
